UNITED STATES PATENT OFFICE.

FRANCIS M. CARTER, OF MARLBOROUGH, MASSACHUSETTS.

SKIVING-MACHINE.

SPECIFICATION forming part of Letters Patent No. 225,340, dated March 9, 1880.

Application filed January 2, 1880.

To all whom it may concern:

Be it known that I, FRANCIS M. CARTER, of Marlborough, county of Middlesex, State of Massachusetts, have invented an Improvement in Skiving-Machines, of which the following description, in connection with the accompanying drawings, is a specification.

This invention relates to machines for skiving leather, and is an improvement on an invention heretofore patented to me, No. 210,183.

My invention consists, essentially, in the employment, in a skiving-machine, of a roller to bear upon the stock being skived, the said roller being so supported, with relation to the bed upon which the material rests and the skiving blade or knife, that the center of rotation of the said roller, as it rises, by reason of increase in the thickness of material being operated upon, is moved backward with relation to the cutting-edge of said blade, so as to always keep the edge of the said blade at the same distance from the said roller, which bears upon the said material being skived, no matter what may be its thickness, and in this way the formation of wrinkles between the acting face or portion of this wheel and the edge of the blade are avoided, especially when skiving very thin material.

In skiving-machines as heretofore constructed the usual roller to bear upon the material just in advance of the cutting-edge of the blade has been so supported as to be moved only in a vertical direction; and it will be obvious, under such construction, that the peripheral portion of the said roller bears upon the said material more or less remote from the edge of the blade, according to the varying thickness of the said material, and consequently, with thin material, bunches or wrinkles are apt to be formed between the wheel and edge of the blade.

In this my machine the roller referred to is also the feeding-roller, and it is mounted upon the end of a rotatable shaft having its bearings, as herein shown, in pivoted arms. The descent of the said roller is limited by a suitable screw.

Figure 1 represents, in front elevation, a skiving-machine constructed in accordance with my invention; Fig. 2, a side elevation

thereof, with part of the overhanging arm broken away to show the bearings for the shaft of the roller, the latter being omitted to show the position of the knife or blade. Fig. 3 is a partial section of the blade-holder on the dotted line, Fig. 2; Fig. 4, a detail, showing the top of the vertically-adjustable bed and the blade-holder; and Fig. 5 is a detail of the roller.

The frame *a*, overhanging arm *b*, post *c*, bed *d*, its shank *e*, and gage *i* are substantially as in my Patent No. 210,183. The roller *g*, which presses upon the material being skived, and which, as herein shown, is also the feeding device, is attached to the forward end of a rotatable shaft, *h*, having its bearings in arms *j k*, pivoted to the arm *b* by screws *l m*. At its rear end shaft *h* has a pinion, *n*, which is held pressed into engagement with the gear-wheel *o*, fast on hub *p* of the driving-wheel *q*, by means of a spring, *r*, made adjustable by screw *s*.

The screw *l* serves as a pivotal point for the bearing *j*, and as the wheel *g* rises and falls it is forced to move in the arc of a circle about the said screw *l*, and consequently backward and forward with relation to the edge 2 of the blade or knife *w*, rather than vertically or at right angles to the top of the bed *d*, as heretofore common; and moving backward and forward with relation to the edge 2, as the roller rises and falls, the said edge and the acting portion of the roller are always kept quite close together, notwithstanding variation in the thickness of the material, which is a matter of much importance, especially with very thin stock, for thereby the formation of wrinkles between the edge 2 and roller is avoided and the skiving is uniform, whereas if wrinkles form the skiving is irregular and wavy.

The regulating device *a'* (shown as a screw) acts to determine the movement of the arm *k*, and consequently the descent of the roller or wheel *g* toward bed *d*, the regulating device being adjusted according to whether thick or thin material is to be skived; but the said roller is free to rise against the stress of the spring *r*.

The roller *g* (see Fig. 5) has diamond-shaped teeth, in order that each tooth may overlap a

tooth of the row next to it. This construction lessens the tendency of the teeth to mar or deface the leather.

The blade w is held between jaws $b^2 c^2$. A bolt, 3, is extended through jaw b^2 , and into and through a bearing, 4, at the top of a shank, 5, made vertically adjustable in a split bearing-sleeve, d^2 , having a horizontal stud, x , which is extended into and made horizontally adjustable in a sleeve or bearing, f^2 , herein shown as cast with the frame a , as is also the post c .

The jaw b^2 may be turned about the bolt 3 as a center, to thereby change the angle at which the blade w is to extend across the rear edge of the bed d , according to the quantity of stock it is desired to remove from the edge of the material being skived, and is held in adjusted position, between the head of the said bolt and the side of the bearing 4, by means of the handled nut g^2 , which is screwed upon the end of the said bolt, as shown in section, Fig. 1.

The sleeve d^2 , split open at its rear side and having two ears, one of which only is shown at d^3 , has a handled bolt, d^4 , extended through the said ears, so as to cause the said sleeve d^2 to clamp and hold the shank 5 in any position to which it may be adjusted vertically, as it is desired to skive thick or thin stock.

30 The bearing d^2 , adapted, as described, to be adjusted horizontally, may be held in adjusted position by means of the handled screw h^2 .

The jaw c^2 , which receives the edge 8 of the blade w , is connected with jaw b^2 by a screw, 35 i^2 , extended through a hole in the jaw c^2 , larger in diameter than the shank of the said screw, in order to permit the said jaw c^2 to be raised or lowered independently of the jaw b^2 when it is desired to give the cutting-edge 2 more 40 or less rake. This is accomplished by the adjusting-screw l^2 , extended loosely through the ear 10 of the jaw b^2 , and screwed into the lug 11 of the jaw c^2 . A spiral spring, 12, about screw l^2 prevents it from being moved accidentally.

45 The large milled nut f^3 of the bed-adjusting screw f is seated and held in a slot between the post c and the bed, as shown clearly in Fig. 2, and as the said nut is turned the screw 50 acts to raise or lower the bed d positively.

The bed d at its top is provided with a removable steel or other plate, m^2 , more durable than cast-iron, to thereby obviate wearing the bed, as would otherwise be the case, as the 55 roller g presses the material against it. This plate m^2 , slid into a groove in the bed, is held in place, as herein shown, by the gage i .

This machine may be used to skive leather, leather-board, and like material.

60 The spring 15, attached to the arm b , and

extended over the top of the guide, prevents the edge of the material being skived from curling up over or working across the top of the guide.

I claim—

65 1. In a skiving-machine, a bed to support the material, a blade to skive it, and a roller to press upon the material in advance of the cutting-edge of the blade, the roller having its supports arranged to permit the said roller, 70 in its rising and falling movements, to also move backward and forward with relation to the cutting-edge of the said blade, in order to obviate the formation of wrinkles between the roller and blade as the material is being skived, 75 substantially as described.

2. The roller g , provided with diamond-shaped teeth to extend one beyond the other at their ends, as shown, substantially as and for the purpose described.

80 3. The roller to bear upon the material, and its shaft h , combined with the movable arms in which the shaft has its bearings, to permit the said roller and shaft, during its rotation, to be moved upward and backward, and vice 85 versa, substantially as described.

4. The combination, with the bed and blade, of a roller to bear upon the material in advance of the cutting-edge of the blade, and the supports for the roller, combined with the regulating device to govern both the downward and forward position of the said roller with relation to the bed and cutting-edge of the blade, substantially as described.

5. In a skiving-machine, the roller-carrying 95 shaft h and its movable supporting-arms, and the pinion n on the said shaft, combined with the rotatable gear o , with which the pinion n is always in engagement, notwithstanding variations in the position of the said shaft and roller, substantially as described.

6. In a skiving-machine, the bed d and roller g , combined with the removable piece m^2 , harder than the said bed, all substantially as and for the purpose described.

105 7. In combination, the blade, jaws $b^2 c^2$, vertically-adjustable bearing 4 and shank 5 , a bolt to hold and adjust the jaws in the bearing 4 , and the sleeve and horizontally-adjustable stud x , and devices to hold the said shank and stud in adjusted position, substantially as and for the purpose described.

In testimony whereof I have signed my name to this specification in the presence of two subscribing witnesses.

FRANCIS M. CARTER.
